RIDING-TYPE LAWNMOWER FRAME

Viktor Schreckengost, Cleveland Heights, Ohio, assignor
to The Murray Ohio Manufacturing Co., Nashville,
Tenn., a corporation of Ohio

Filed Sept. 5, 1969, Ser. No. 19,032

Term of patent 14 years

Int. Cl. D8—01

U.S. Cl. D40—1

Fig. 1

Fig. 2

Fig. 3

FIG. 5

FIG. 6

FIG. 1 is a top plan view of a riding-type power lawnmower frame;

FIG. 2 is a side elevational view thereof;

FIG. 3 is a side elevational view thereof taken from the side opposite that shown in FIG. 2;

FIG. 4 is a bottom plan view thereof;

FIG. 5 is a front elevational view thereof; and

FIG. 6 is a rear elevational view thereof.

I claim:

The ornamental design for a riding-type lawnmower frame, substantially as shown.
